Application August 3, 1936, Serial No. 94,092

7 Claims. (Cl. 312—174)

This invention relates to ovens, and more particularly to an adjustable or shiftable shelf which is mounted in the oven and so connected with the door of the oven that when the door is open the shelves will be shifted outwardly to a position in which articles may be easily placed upon or removed from the trays.

Another object of the invention is to so mount the trays and so connect them with the door of the oven that when the door is open, the trays will not only be shifted longitudinally of the oven in an outwardly moving direction, but also have upward movement imparted to them and thus lift the frame of the trays out of engagement with the bottom of the oven and prevent wear upon the frame by scraping engagement with the bottom of the oven.

It is another object of the invention to so mount the frame of the trays that during opening or closing of the oven door, the frame and the trays carried thereby will be maintained in substantially a horizontal position and thus prevent spilling of the contents of pans placed upon the trays.

Another object of the invention is the provision of a device of this character which is simple in construction and may be very easily applied to an oven of a conventional construction.

The invention is illustrated in the accompanying drawings, wherein

Figure 1 is a sectional view taken vertically through an oven with the door closed and the trays housed within the oven.

Figure 2 is a view similar to Figure 1 showing the door swung outwardly to an open position and the trays moved outwardly with the door.

Figure 3 is a sectional view taken horizontally through Figure 2 along the line 3—3.

Figure 4 is a sectional view taken along the line 4—4 of Figure 2.

Figure 5 is a fragmentary view illustrating the manner in which end portions of bars or strips are connected to form an upper corner portion of the frame.

Figure 6 is a perspective view illustrating the manner of connecting the rear corner posts with the upper side bars of the frame.

The stove, which is indicated in general by the numeral 1, is of a conventional construction and has a baking compartment or oven 2 located over a lower compartment 3 in which burners or heating units of a conventional construction are to be mounted. The frame of the

trays has a bottom plate 4 which serves as a lower tray, front and rear corner posts 5 and 6 and upper side bars 7 upon which the upper tray 8 rests. The bottom plate 4 is formed of sheet metal and has marginal portions bent to provide depending flanges 9 along its sides and front and rear ends. The corner posts 5 and 6 are formed of angle metal and are disposed vertically at corners of the bottom plate with their lower ends riveted to the depending side and end flanges of the bottom plate. At their upper ends, the front corner posts are split and their front flanges bent to form rearwardly extending tongues 10 upon which rest the inwardly extending horizontal flanges of the side bars 7 which are also formed of angle metal. Forward ends of the horizontal flanges of the side bars are riveted to the tongues 10, as shown at 11, while the vertically extending flanges of the side bars are riveted against the inner faces of the upwardly projecting side flanges of the corner posts, as shown at 12. The rear corner posts 6 are also split from their upper ends and their side flanges bent inwardly to form tongues 13 upon which rest rear end portions of the horizontal flanges of the side bars. The vertical flanges of the side bars project rearwardly beyond the horizontal flanges thereof and are bent inwardly to form tongues 14 which bear against the upper end portions of the rear flanges of the rear corner posts. Rivets 15 have been shown as means for rigidly securing rear end portions of the side bars to upper end portions of the rear corner posts but it is to be understood that welding may be used in place of rivets and also that the forward end portions of the side bars may be secured to upper ends of the corner posts by welding instead of by rivets. By forming the side bars 7 and the front and rear corner posts of angle metal and securing front and rear ends of the side bars to the corner posts, as shown in Figures 5 and 6, the side bars will constitute tracks open at their forward ends and having abutments at their rear ends. Therefore, the upper tray or grid 8 may be easily set in place upon the inwardly extending horizontal flanges of the tracks or side bars and slid longitudinally into position to rest thereon, as shown in Figures 3 and 4. When it is desired to remove this upper tray or grid, it can be grasped at its front end and drawn forwardly along the horizontal flanges of the side bars and then lifted out of place. It may then be thoroughly cleaned and returned to the side bars. If so desired, side bars corresponding to the

- side bars 7, and a rear corner bar may be employed in place of the bottom plate 4 and a removable tray or grid corresponding to the tray 8 set in place thereon.
5. The frame and trays are to be mounted for shifting movement as a unit longitudinally of the oven from the housed or retracted position shown in Figure 1 to the extended position shown in Figure 2 when the door 16 of the oven is open.
10. In order to do so, there have been provided runners 17 which are formed of angle metal and have rear ends of their vertically disposed flanges pivoted to lower ends of metal links 18, the upper ends of which are pivoted to the vertically disposed flanges of the side bars 7, as shown at 19. The forward end portions of the vertically disposed flanges of the runners 17 project beyond the horizontal flanges thereof, as shown in Figures 1 and 2, to provide arms 20, the forward ends of which are pivoted to the rear ends of metal strips 21. These strips 21 are welded or otherwise firmly secured in crossed and transversely extending relation to metal arms 22 which are substantially triangular in shape and at their lower ends are formed with inwardly projecting flanges 23 welded or otherwise firmly secured against the inner face of the door in spaced relation to the hinged ends thereof. It will thus be seen that the frame of the device is pivotally connected with rear arms 18 and front arms 22 to which the runners 17 are also connected and that when the oven door is swung outwardly and downwardly from the closed position shown in Figure 1 to the open position shown in Figure 2, the arms 22 will exert lifting and pulling action upon the frame, while the runners will be slid longitudinally. The fact that upper ends of the brackets or arms 22 are pivoted to the brackets 24 carried by the side bars 7 of the frame provides a very good pivotal connection between these parts and permits the front end portion of the frame to be easily lifted and the frame shifted forwardly out of the oven when the door is swung downwardly to the open position. Attention is further called to the fact that as the door is swung outwardly and downwardly towards the open position, the relation of the pivotal connection 25 to the hinges 26 of the door will cause the forward end portions of the runners to be lifted. Therefore, during outward and downward swinging movement of the door, only the rear ends of the runners will rest upon the bottom of the oven and the runners may move very easily from the retracted position of Figure 1 to the extended position of Figure 2. The frame is lifted bodily from the runners during the outward movement by the swinging movement of the arms 18 and the arms or brackets 22 and maintained in substantially horizontal position. Therefore, articles placed in the oven upon the upper tray 18 or the lower tray 4 will not be liable to roll off of the same or become spilled due to tilting of a dish. An improved oven tray and actuating means therefor has been provided which may be very easily applied to an oven of a conventional construction. It will also be noted that the device operates very easily as frictional resistance is reduced to a minimum and that when the oven door is opened, the frame and trays carried thereby will be shifted outwardly to a position in which articles may be placed upon or removed from the trays without reaching into the hot oven.
- Having thus described the invention, what is claimed as new is:
75. 1. In a device of the character described, a structure defining a chamber open at its front, a door for closing the open front of the chamber hinged at its lower end, runners in said chamber shiftable longitudinally thereof, a frame, links pivoted to said runners and to said frame, and arms carried by said door and pivotally connected with the frame and said runners for shifting the runners longitudinally and moving said frame to an extended position out of the open front of the chamber when the door is swung downwardly to an open position.
2. In a device of the character described, a casing defining a chamber open at its front, a door for closing the open front of the chamber hinged at its bottom, runners resting upon the bottom of said chamber and free to move relative to the same, a frame over said runners, links pivoted to the runners and rear portion of said frame, arms carried by said door in spaced relation to the hinged end thereof and pivotally connected with the forward portion of said frame, and side extensions for said arms pivoted to front ends of said runners.
3. In a device of the character described, a casing defining a chamber open at its front, a door for closing the front end of said chamber hinged at its lower end, runners in said chamber freely movable relative to the bottom of the chamber, a frame over said runners, links pivotally connected with the frame and runners, and actuating means carried by said door and connected with the frame and runners for tilting the runners upwardly at their front ends by swinging the frame upwardly and then shifting the frame and runners outwardly to an extended position and disposing the runners at rest upon the bottom of the chamber while swinging the door outwardly and downwardly to an open position.
4. In a device of the character described, a body defining a chamber open at its front, a door for said chamber hinged at its lower end, runners in the chamber freely movable relative to the bottom thereof and connected with the door in spaced relation to the hinged end thereof whereby the runners will be tilted upwardly at their front ends and then moved outwardly and brought to rest upon the bottom of the chamber in overlying relation to the door when the door is fully open, and a frame connected with the runners and door to cause the frame to swing upwardly and then longitudinally out through the open end of the chamber to a position over the door when the door is swung downwardly to an open position.
5. In a device of the character described, a casing defining a chamber open at its front, a door having its lower end hinged to the casing at the bottom of the open end of the chamber, arms carried by and projecting from said door to extend into the chamber when the door is closed, strips extending transversely of said arms adjacent the door and projecting downwardly from the arms when the door is closed, runners in said chamber resting upon but free from the bottom thereof and having their front ends pivoted to said strips, a frame over said runners, links of rigid material pivoted at their lower ends to rear ends of said runners and at their upper ends to said frame adjacent the rear end thereof, and means pivotally connecting ends of said arms with said frame adjacent the front end thereof.
6. In a device of the character described, a casing defining a chamber open at its front, a door having its lower end hinged to the casing at the bottom of the open end of the chamber, arms

secured against the inner face of said door adjacent opposite sides thereof and in spaced relation to the hinged end of the door, a strip carried by each arm and extending transversely thereof with a portion projecting from the arm, a frame in said chamber having upper and lower trays, runners in said chamber under said frame extending longitudinally of the chamber and resting upon the bottom of the chamber in position to engage under side portions of the frame, links pivoted to rear ends of said runners and to the rear upper portion of said frame, front ends of the runners being pivoted to said strips, and means pivotally connecting said arms with the upper side portions of said frame adjacent the front end thereof.

7. In a device of the character described, a casing defining a chamber open at its front, a door having its lower end hinged to the casing at

the lower end of the open front of said chamber, arms secured to the inner face of said door adjacent opposite sides thereof and in spaced relation to the hinged end of the door, runners in said chamber resting upon but unsecured to the bottom thereof and having their outer ends pivotally connected with said arms, a frame having a bottom plate, corner posts rising from the bottom plate, side bars extending between and secured to upper ends of the corner posts, the side bars defining runners closed at their rear ends and open at their front ends, a grill resting upon said runners, links pivoted to the rear ends of said runners and to the side bars of the frame adjacent the rear ends thereof, and brackets carried by the side bars in spaced relation to the front ends thereof and pivoted to said arms.
